US00D905601S

(12) **United States Design Patent** (10) **Patent No.:** **US D905,601 S**
Cheung et al. (45) **Date of Patent:** **** Dec. 22, 2020**

(54) **CASE**(71) Applicant: **JUUL Labs, Inc.**, San Francisco, CA (US)(72) Inventors: **Brandon Cheung**, San Francisco, CA (US); **Richard Johnson**, San Francisco, CA (US); **Kevin Lomeli**, Oakland, CA (US); **James Monsees**, San Francisco, CA (US); **Alexander Ringrose**, Oakland, CA (US); **Roxolana Wacyk**, San Francisco, CA (US)(73) Assignee: **JUUL Labs, Inc.**, San Francisco, CA (US)(***) Term: **15 Years**(21) Appl. No.: **29/697,543**(22) Filed: **Jul. 9, 2019****Related U.S. Application Data**

(63) Continuation of application No. 29/638,723, filed on Feb. 28, 2018, now Pat. No. Des. 860,523.

(51) **LOC (12) Cl.** **27-02**(52) **U.S. Cl.**USPC ..... **D12/172**(58) **Field of Classification Search**

Primary Examiner — Marissa J Cash(74) *Attorney, Agent, or Firm* — Mintz Levin Cohn Ferris Glovsky and Popeo, P.C.(57) **CLAIM**

The ornamental design for a case, as shown and described.

DESCRIPTION

FIG. 1 is a front, right side, and top perspective view of a case of our design;

FIG. 2 is a front, left side, and bottom perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The dash-dash broken lines illustrate portions of the case that form no part of the claimed design.
